UNITED STATES PATENT OFFICE.

GEORGE H. ZOUCK, OF ORANGE, NEW JERSEY, ASSIGNOR TO AIR REDUCTION COMPANY,
INCORPORATED, A CORPORATION OF NEW YORK.

CUTTING-BLOWPIPE.

1,310,101.

Specification of Letters Patent. Patented July 15, 1919.

Application filed October 28, 1918. Serial No. 259,892.

To all whom it may concern:

Be it known that I, GEORGE H. ZOUCK, a citizen of the United States, residing at Orange, in the county of Essex, State of New Jersey, have invented certain new and useful Improvements in Cutting-Blow-pipes; and I do hereby declare the following to be a full, clear, and exact description of the invention, such as will enable others skilled in the art to which it appertains to make and use the same.

This invention relates to cutting blow-pipes or torches, and has for its primary object the provision of an inexpensive, simple and efficient blow-pipe structure, capable of employment in cutting operations, having the gas inlet passages securely sealed to prevent premature mixing of the gases and including a replaceable tip so constructed as to insure a proper relation by volume of combustible and oxidizing gases delivered to the heating jet discharge passages.

Further objects and advantages of my invention will be apparent, as it is better understood, by reference to the following specification, when read in connection with the accompanying drawing, illustrating the preferred embodiment thereof, in which Figure 1 is a longitudinal section through the head and tip of a cutting blow-pipe or torch; Fig. 2 is a transverse section through the head, and Fig. 3 is an end elevation of the tip.

Numerous forms of blow-pipes have been heretofore designed involving many different structures, but so far as applicant is aware, all have been subject to one or more of such disadvantages as leakage and premature mixing of the gases, liability to backfiring and general expensiveness of construction, due to the number of parts employed and to intricacy of operations necessary in manufacturing. The blow-pipe forming the subject matter of the present application has been devised to overcome all of these numerous difficulties and to provide a structure which embodies, with the utmost simplicity, all of the desirable characteristics of an efficient cutting blow-pipe capable of long continued use to perform its desired function.

Referring to the drawing, 5 indicates a head to which pipes 6, 7 and 8 are secured, the pipes 6 and 7 being adapted to separately convey supplies of oxygen to the head while

the pipe 8 carries a supply of combustible gas. Within the head 3, passages 9, 10 and 11 are provided communicating respectively with the pipes 6, 7 and 8. The passage 9 is axially disposed within the head and terminates at the apex of a projecting conical seat, while the passages 10 and 11 terminate in channels 12 and 13 in and dividing such seat into a plurality of conical surfaces 14, 15 and 16.

The tip 17 comprises a single piece having a longitudinal bore or discharge passage 18 for the cutting jet, axially disposed and adapted to align with the passage 9 in the head. A plurality of heating jet discharge passages 19 are arranged about the discharge passage 18 and, at their inner ends, communicate with the channel 12 in the head, when the tip is held in assembled relation with the head by a threaded nut 20. The inner end of the tip is provided with a conical recess conforming to the conical surfaces 14, 15 and 16, and adapted, when engaged therewith, to form gas-tight seals between the respective passages 9, 10 and 11, and between the latter and the wall of the head, to permit the passage of gas from the channel 13 to the channel 12 and provide a series of grooves or depressions 21, which may be formed by a milling operation or by pressing, in the face of the conical seat, at the inner end of the tip.

As will be readily understood, the oxygen supplied through the passage 9 is delivered directly to the cutting jet discharge passage 18 of the tip. The combustion supporting oxygen is delivered from the passage 10 in the head to the channel 12, and thence to the heating jet discharge passages 19. The combustible gas is delivered from the passage 11 in the head to the channel 13, and thence through the grooves or depressions 21 to the channel 12, where it is mixed with the combustion supporting oxygen, before the latter enters the heating jet discharge passages 19. The result is a thorough and complete mixture of the heating gases before they are discharged from the tip.

Tips having discharge passages of different sizes are normally employed with the same head, the tips being interchangeable and replaceable by simply removing the nut 20. By properly proportioning the grooves or depressions 21, any desired mixture of oxygen and combustible gas suitable to the

size of the discharge passages 19, which are proportioned to the size of the discharge passage 18, may be provided for, and a proper mixture is always insured. The seals 5 formed by engagement of the face of the conical recess in the inner end of the tip with the conical surfaces in the head, insures an absolutely gas-tight joint, so that 10 premature mixing of the gases, or escape thereof, other than through the intended discharge passages, is prevented.

The structure is extremely simple, requiring a minimum number of manufacturing operations, as will be readily apparent in inspection of the drawing. The only wear which occurs in the normal use of the structure is at the point of engagement of the nut 20 with the shoulder of the tip. Wear, at this point, is, however, of no importance, 20 since it does not affect the operation of the blow-pipe. Should the tip be injured by misuse, it may be readily replaced and the blow-pipe may thus be restored to its original condition.

25 While the preferred embodiment of the invention has been shown, it will be understood that various changes in the details of construction may be made, without departing from the principle of the invention.

30 I claim:

1. In a device of the character described, the combination of a head having two passages for oxygen, one for combustible gas and a projecting conical seat, a tip having 35 a conical recess at its inner end conforming to said seat and forming therewith a gas-tight joint, a cutting jet discharge passage disposed in alinement with one of the oxygen passages in said head, a heating jet 40 discharge passage communicating with the other oxygen passage in said head and a groove or depression in the face of said recess, whereby combustible gas is conveyed to and mixed with the oxygen issuing from 45 said last mentioned oxygen passage and means for holding said tip in assembled relation with said head.

2. In a device of the character described, the combination of a head having two passages for oxidizing gas, one for combustible gas and a projecting conical sealing surface, a tip having a conical surface conforming to said sealing surface and forming therewith a gas tight joint, a cutting jet 50 discharge passage communicating with one of the oxidizing gas passages, and a heating jet discharge passage communicating with the other oxidizing gas passage, and a groove or depression in one of said surfaces 55 whereby combustible gas is conveyed to and mixed with oxidizing gas before entering said heating jet discharge passage when said tip is held in assembled relation with said head.

60 3. In a device of the character described,

the combination of a head having two passages for oxygen, one for combustible gas and a projecting conical seat, a tip having a conical recess at its inner end conforming to said seat and forming therewith a gas-tight joint, a cutting jet discharge passage communicating directly with one of the passages in said head, a plurality of heating jet discharge passages and grooves or recesses in the face of said depressions whereby combustible gas is conveyed to and mixed with 70 oxygen before entering said heating jet discharge passages and means for holding said tip in assembled relation with said head. 75

4. In a device of the character described, 80 the combination of a head having two passages for oxygen, one for combustible gas, a projecting conical seat, and channels in said seat communicating respectively with an oxygen and a combustible gas passage, a tip 85 having a conical recess conforming to said seat and forming therewith a gas-tight joint, a cutting jet discharge passage communicating with one of the oxygen passages in said head, a plurality of heating jet discharge 90 passages communicating with one of said channels and a plurality of grooves or depressions in the face of said conical recess connecting said channels whereby combustible gas is conveyed to and mixed with 95 oxygen before entering said heating jet discharge passages and means for holding said tip in assembled relation with said head.

5. In a device of the character described, 100 the combination of a head having a projecting conical seat, a passage for oxygen terminating at the apex of said seat, channels in said seat and passages for oxygen and combustible gas respectively terminating in said channels, a tip having a conical recess conforming to said seat and forming therewith a gas tight joint; a cutting jet discharge passage having its mouth at the apex of said conical recess, heating jet discharge 105 passages communicating with one of said channels, grooves or depressions in the face of said conical recess connecting said channels and means for holding said tip in 110 assembled relation with said head.

6. In a device of the character described, the combination of a head having a sealing surface and a plurality of passages terminating therein, two of said passages conveying oxidizing gas and the other combustible gas, a tip having a surface at its inner end conforming to said sealing surface and forming therewith a gas-tight joint, a cutting jet discharge passage communicating with one of the passages in said head, a heating jet discharge passage and a groove or depression in 120 one of said surfaces, whereby oxidizing and combustible gases are mixed before entering said heating jet discharge passage when said tip is held in assembled relation with said head. 125 130

7. In a device of the character described, the combination of a head having a seat and a plurality of passages terminating therein, two of said passages conveying oxygen and the other combustible gas, a tip having a seat at its inner end conforming to the seat in said head and forming therewith a gas-tight joint, a cutting jet discharge passage communicating directly with one of the passages in said head, heating jet discharge passages and grooves or depressions in the seat at the inner end of said tip whereby oxygen and combustible gas are mixed before entering said heating jet discharge passages and means for holding said tip in assembled relation with said head. 55
8. In a device of the character described, the combination of a head having a projecting seat and a plurality of passages terminating therein, two of said passages conveying oxygen and the other combustible gas, a tip having a recess conforming to and forming with said seat a gas-tight joint, a cutting jet discharge passage communicating with one of the passages in said head, heating jet discharge passages and grooves or depressions in the face of said recess whereby oxygen and combustible gas are mixed before entering said heating jet discharge passages and means for holding said tip in assembled relation with said head. 60
9. In a device of the character described, the combination of a head having a projecting seat and a plurality of passages terminating therein, two of said passages conveying oxygen and the other combustible gas, a tip having a recess conforming to and forming with said seat a gas-tight joint, a cutting jet discharge passage communicating with one of the passages in said head, a heating jet discharge passage and a groove or depression in said surface, whereby combustible gas is conveyed to and mixed with oxidizing gas issuing from the other oxidizing gas passage in said head before entering said heating jet discharge passage when said tip is held in assembled relation with said head. 65
10. In a device of the character described, the combination of a head having a projecting seat and a plurality of passages terminating therein, two of said passages conveying oxygen and the other combustible gas, a tip having a surface conforming to said seat, a cutting jet discharge passage communicating with one of the oxidizing gas passages in said head, a heating jet discharge passage and a groove or depression in said surface, whereby combustible gas is conveyed to and mixed with oxidizing gas issuing from the other oxidizing gas passage in said head before entering said heating jet discharge passage when said tip is held in assembled relation with said head. 70
11. A device of the character described, comprising a head having a projecting seat, two passages for oxidizing gas and a passage for combustible gas terminating in said seat and forming therewith a gas-tight joint, 75 and a tip having a surface conforming to said seat, a cutting jet discharge passage communicating with one of the oxidizing gas passages in said head, a heating jet discharge passage and a groove or depression in said surface, whereby combustible gas is conveyed to and mixed with oxidizing gas issuing from the other oxidizing gas passage in said head before entering said heating jet discharge passage when said tip is held in assembled relation with said head. 80
12. A device of the character described, comprising a head having a seat, two passages for oxidizing gas and a passage for combustible gas terminating therein and a tip having a surface conforming to said seat and forming therewith a gas tight joint, a cutting jet discharge passage communicating with one of the oxidizing gas passages in said head, a heating jet discharge passage and a groove or depression in said surface whereby combustible gas is conveyed to and mixed with oxidizing gas issuing from the other oxidizing gas passage in said head, said surface coöperating with said seat beyond the ends of said groove to prevent the escape of gases when said tip is held in assembled relation with said head. 85
- 50 10. In a device of the character described,

In testimony whereof I affix my signature.
GEORGE H. ZOUCK.
